DESIGN FOR A GAME BOARD

Clyde M. Swarr, Lancaster, Pa.

Application April 11, 1945, Serial No. 118,951

Term of patent 14 years

(Cl. D34—5)

To all whom it may concern:

Be it known that Clyde M. Swarr, a citizen of the United States of America, residing at Lancaster, in the county of Lancaster and State of Pennsylvania, has invented a new, original, and ornamental Design for a Game Board, of which the following is a specification, reference being had to the accompanying drawing forming part of this specification.

Fig. 1 is a plan view of the game board showing my new design.

Fig. 2 is a side elevational view thereof.

Portions of the drawing are lined for contrasting colors.

I claim:

The ornamental design for a game board, as shown and described.

CLYDE M. SWARR.
